UNITED STATES PATENT OFFICE.

WILLIAM DUTCH, OF SAN FRANCISCO, CALIFORNIA.

HEAD-LIGHT.

SPECIFICATION forming part of Letters Patent No. 364,401, dated June 7, 1887.

Application filed July 10, 1883. Renewed April 30, 1885. Again renewed March 18, 1887. Serial No. 231,470. (No model.)

To all whom it may concern:

Be it known that I, WILLIAM DUTCH, of the city of San Francisco, county of San Francisco, State of California, have invented an Improvement in Head-Lights; and I hereby declare the following to be a full, clear, and exact description thereof.

My invention relates to an adjustable head-light to be used on locomotives, vessels, and for other purposes; and it consists of a lantern mounted upon the front of the locomotive with a mechanism and means for operating the same, so that it may be turned and concentrate the light at any desired point at either side of the track or vertically up or down, as will be more fully explained by reference to the accompanying drawings, in which—

Figure 1 is a plan view showing a line of track and a train of cars with my adjustable head-light. Fig. 2 is a front elevation. Fig. 3 is a plan. Fig. 4 is a side elevation and a transverse section through the hollow shaft E and shaft K. Fig. 5 is a sectional elevation.

In the usual construction and use of head-lights for locomotives they are fixed to the front of the engine, so that the light is always thrown forward and concentrated in one line. This shows the track clearly enough when the line is straight; but if there are sharp curves the line of direction will throw the light outside of the line of the rails within a few yards in some cases and leave the line of the track or the inner line or embankment of the curve in comparative darkness. To overcome this difficulty and to provide an adjustment which will allow the engineer to direct the light to various points off the line, the lantern A is supported upon a platform or frame which may have a movement to right or left about a vertical axis, or up and down about a horizontal axis. This may be accomplished in various ways. In the present case I have shown a vertical spindle or standard, B, which is journaled or supported so as to be capable of movement from side to side about a vertical axis. A bevel-gear-wheel, C, is fixed to this standard and is engaged by a similar bevel-gear, D, upon the end of the short shaft E, and this has a bevel-wheel, D', at the opposite end, engaging a similar gear, F, upon the shaft G, which extends back to a point within easy reach of the engineer.

In the present case I have shown the shafts E and G made hollow, the latter forming a hand-rail upon one side of the boiler, and it has a hand-wheel, H, by which it may be turned, and, through the bevel-gears C and D, it will turn the lantern, so that the light thrown forward and concentrated by the reflector may be directed to any desired point.

It is often desirable to throw the light up or down, as well as to the right or left, and I have therefore fixed a smaller gear-wheel, I, to the standard which supports the lantern, and this is engaged by another gear wheel or pinion, J, which is fixed to the shaft K, turning within the hollow shaft E. Another shaft, L, extends through this hollow rail-shaft G, and terminates within reach of the engineer, with a hand-wheel, M, similar to the wheel H, each of them being operated independently of each other. The shaft O of the pinion I passes through the hub of the wheel C and has a gear-wheel, P, fixed to its inner end, which engages a curved rack, R, to produce the vertical movement, mounted in a curved guide-plate, b, of the standard or upright B.

A bevel-gear, N, with one wheel upon the shaft L and the other, N', upon the shaft K, serves to transmit the motion given the hand-wheel M to the lantern-frame and tilt it up or down about a horizontal axis. When the lantern is to be moved from side to side, both sets of gears must be moved together, which is done by grasping both parts of the divided wheel H; but when the wheel M is turned to move the vertical gear only the rear half of wheel H will be turned, the other half, with the horizontal gears, remaining stationary. By this arrangement the engineer is enabled to examine dangerous or doubtful parts of the road, and in stormy weather to turn the light upon threatening trees or masses of earth or rock upon either side which may be in danger of falling, so that if they appear in a dangerous condition he may instantly check his speed, or stop. This device also enables him to turn the lantern so as to throw the light across sharp corners and examine the line of track at some distance ahead of the train and at points which would be entirely out of reach of the light in its usual fixed position.

It will be manifest that a lantern or head-light having a similar adjusting mechanism

might be mounted upon a vessel and would be of great advantage when running in crowded harbors or channels, or in making landings at wharves or docks, as the light could be turned 5 to either side, and collisions or accidents avoided. This mechanism may also be employed for other similar purposes—as in hydraulic-mining claims which are to be worked at night, and when different portions are to be 10 examined.

Having thus described my invention, what I claim as new, and desire to secure by Letters Patent, is—

1. The combination, with the lantern A, of 15 the vertical supporting standard provided with gear-wheel C, horizontal shaft E, arranged at right angles to standard B and having mounted thereon gear-wheels D and D', and horizontal shaft G, arranged at right angles to shaft E and extending along parallel with and at one side of the boiler of an engine, and provided with gear-wheel F and hand-wheel H, substantially as and for the purpose herein shown and described.

2. The combination, with the lantern A, of 25 the curved rack R, shaft O, having gear-wheel P and pinion I, shaft K, provided with gear-wheels J N, and shaft L, provided with gear-wheel N' and hand-wheel M, substantially as and for the purpose herein shown and de- 30 scribed.

3. The combination, with the lantern A, of the standard B, provided with gear-wheel C, hollow shaft E, having gear-wheels D D', hollow shaft G, provided with gear-wheel F, 35 curved rack R, shaft O, having gear-wheel P and pinion I, shaft K, provided with gear-wheels J N, shaft L, provided with gear-wheel N', and the divided hand-wheel H, substantially as herein shown and described.

In witness whereof I have hereunto set my hand.

WILLIAM DUTCH.
